UNITED STATES PATENT OFFICE

149,055

DESIGN FOR A LACE OR SIMILAR ARTICLE

Otto Frei, New York, N. Y., assignor to Otto A. Scheurmann, Bayside, N. Y.

Application July 25, 1947, Serial No. 140,499

Term of patent 7 years

(CL. D47—6)

To all whom it may concern:

Be it known that I, Otto Frei, a citizen of the United States of America, residing in New York city, county of New York, and State of New York, have invented a new, original, and ornamental Design for a Lace or Similar Article, of which the following is a specification, reference being had to the accompanying drawing, forming part thereof.

In the drawing:

The figure is a plan view of a piece of lace embodying the design.

The lace is shown against a dark background in order to bring out the design. The design is repeated horizontally on the drawing.

I claim:

The ornamental design for a lace or similar article, substantially as shown and described.

OTTO FREI
